UNITED STATES PATENT OFFICE.

CHARLES V. HOGAN, OF CLEVELAND, OHIO, ASSIGNOR OF ONE-HALF TO THE W. S. GILKEY PRINTING COMPANY, OF CLEVELAND, OHIO, A CORPORATION OF OHIO.

CARTON-ASSEMBLING DEVICE.

1,407,864.

Specification of Letters Patent. Patented Feb. 28, 1922.

Application filed July 8, 1920. Serial No. 394,792.

To all whom it may concern:

Be it known that I, CHARLES V. HOGAN, a citizen of the United States, resident of Cleveland, county of Cuyahoga and State 5 of Ohio, have invented new and useful Improvements in Carton-Assembling Devices, of which the following is a specification, the principle of the invention being herein explained and the best mode in which I have 10 contemplated applying that principle, so as to distinguish it from other inventions.

My invention relates to devices used for assembling or forming paper cartons, its object being to provide a device of said 15 character which will be simple in construction and efficient in the performance of its function. The invention consists, generally speaking, of a stationary platen adapted to fit upon the interior of the carton, together 20 with a pressure member adapted to be moved toward and from the upper surface of the platen, and to co-operate with the latter to exert pressure upon the flaps of the carton when pasted in place.

25 These cartons are at the present time furnished the user in flat form so as to economize space in shipping and storing prior to being used. In such flat form, the carton consists of a front and back member and 30 two end members, the top and bottom of each member being provided with a flap which is adapted to be turned inwardly at right angles with said front, back and end members, so as to overlap, in which position 35 they are glued or otherwise secured, all as will hereinafter appear.

The said invention furthermore consists of means hereinafter fully described and particularly set forth in the claims.

40 The annexed drawings and the following description set forth in detail certain means embodying my invention, the disclosed means, however, constituting but one of the various mechanical forms in which the principle of the invention may be applied.

In said annexed drawings:

Figure 1 represents a plan of a battery of devices, each of which embodies my invention.

50 Figure 2 represents a front elevation of such battery.

Figure 3 represents, upon an enlarged scale, a plan of one of the devices embodying the invention.

55 Figure 4 represents a section taken upon

the plane indicated by line IV-IV, in Figure 3, a platen-supporting post being shown broken away.

Figure 5 represents, upon the same scale as Figure 3, a paper carton in so-called "knock-down" form.

Figure 6 represents a perspective view of such carton opened up to assume its rectangular position, and showing the flaps extending in their unfolded position therefrom; and

Figure 7 represents a perspective view showing one set of flaps secured in place.

In the illustrated embodiment of my invention, particularly in Figures 1 and 2, I 70 have shown a series of duplicate devices, each one of which embodies my invention, it being preferable to erect these devices in series so that they may be used in succession.

75 Each of said devices comprises an upright bar 1, Figure 4, which is provided with a vertical slot 2, Figure 2. To the top of this bar is secured a rectangular platen 3 whose dimensions are such that it may be 80 inserted in the interior of a carton when the latter is caused to assume the form shown in Figure 6. This platen is secured in place by means of bolts 4 and wing nuts 5, which bolts pass through angle irons 6 85 secured to the upper end of the post, as shown. The platen 3 may, therefore, be removed when required, and a platen of different dimensions substituted therefor, so as to conform with the requirements of different sizes of cartons. The upper ends or 90 heads of the bolts are seated in a countersunk bore, so as to leave a flat, unobstructed upper surface on the platen.

95 Below the platen is a transverse supporting bar 7, Figure 4, which is secured to the post 1 by means of a bolt 8 passing through the slot 2, and a wing-nut 9, as shown. It will, therefore, be seen that the said supporting bar 7 may be adjusted vertically so 100 as to assume various positions as may be required. This bar is extended as shown in Figure 2, so as to answer as a support for each of the devices constituting the entire battery.

105 Adjacent to the rear of the device is a horizontal bar 10, to the front face of which is hinged a pressure member consisting of a rectangular plate 11, to the upper surface of which is secured the bar 12, the rear end of 110

which is hinged to the bar 10, as shown in Figure 4. This bar 12 is formed with a rectangular aperture 13, which receives a vertical post 14 to the upper end of which 5 is secured a catch 15. This catch co-operates with the spring bolt 16 to lock the pressure member in place, as will herein-after appear.

The dimensions of the plate 11 are those 10 suitable for the largest size carton to be handled by the device, and are shown in the accompanying drawings as substantially the same as the dimensions of the platen 3. The latter is placed in a position such that when 15 the spring bolt 16 engages the catch 15, the plate 11 and platen 3 will be substantially parallel, with just enough space between them to permit the flaps of the carton in their folded position to lie between them 20 under pressure.

The bar 10 is also extended, as shown, so as to answer for all of the devices, and as many upright bars 14 are provided as there are such devices. Suitable base members 17 25 and 17' are provided, upon the former of which upright frame bars 18 are secured, upon which the rear bar 10 is mounted. The upright bars 14 are mounted on the front base member 17'. Transverse base members 30 19 connect the base members 17 and 17', and centrally of the ends of the members 19, the upright bars 1 are secured.

In utilizing the above device, a carton 35 which is shown in its folded condition in Figure 5, is distended to assume the position shown in Figure 6. The pressure member 11 of the particular device of the battery which is to be used is then raised into the position shown by 20, Figure 2, and the carton set down over the platen 3 so that the lower ends of the lower flaps will rest upon the supporting bar 7. This bar is set in a position such that when so supporting the carton, the upper flaps of the latter will project above the upper surface of the platen 3. The end flaps are then bent inwardly and a 40 suitable glue or other adherent applied to their upper surfaces. The front and rear flaps are then folded down upon the end 45 flaps and the pressure member then brought 50

down upon the flaps so folded, and the spring bolt 16 allowed to engage the catch 15. The pressure member thus holds the flaps in place until the glue or other adherent 55 has dried, after which the pressure member may be released and the carton, in the form shown in Figure 7, removed. Such carton is then ready to receive its contents, after which the other flaps are secured in place in the usual manner, it being not necessary to 60 utilize my improved forming device for this purpose since the contents of the carton form a sufficient base to allow the flaps to be pasted in place and a suitable weight to be imposed thereon and permitted to remain until the 65 adherent has dried.

What I claim is:

1. In a carton assembling device, the combination of a plurality of vertical supports; an auxiliary transverse support adjustable 70 vertically of said first mentioned supports, carton receiving platens mounted upon the tops of said vertical supports and pressure members mounted for movement toward and from said platens.

2. In a carton assembling device, the combination of a plurality of stationary platens adapted to receive cartons, an adjustable auxiliary support common to said platens for supporting cartons with their flaps in position to be folded over said platens and individual clamping members co-operating with said platens to clamp said flaps in place upon said platens, said clamping members being movable from clamping position over 80 said platen to a position wholly to one side of said platen.

3. In a carton assembling device, the combination of a row of standards of equal height; carton receiving platens secured to 90 the tops of said standards; a longitudinal rail supported adjacent to and parallel with said platens; clamping members for each of said platens pivoted to said longitudinal rail; means for retaining said clamping members in clamping position and a supporting bar adjustably mounted on said standards below said platens.

Signed by me, this 18th day of June, 1920.
CHARLES V. HOGAN.
